G. GODDU,
MACHINE FOR MAKING FASTENINGS,
APPLICATION FILED JAN. 29, 1916.

1,348,864.

Patented Aug. 10, 1920.

UNITED STATES PATENT OFFICE.

GEORGE GODDU, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR MAKING FASTENINGS.

1,348,864.

Specification of Letters Patent. Patented Aug. 10, 1920.

Application filed January 29, 1916. Serial No. 75,080.

to whom it may concern:

Be it known that I, GEORGE GODDU, a citizen of the United States, residing at Winchester, in the county of Middlesex and 5 State of Massachusetts, have invented certain Improvements in Machines for Making Fastenings, of which the following description, in connection with the accompanying drawings, is a specification, like reference 10 characters on the drawings indicating like parts in the several figures.

This invention relates to machines for making fastenings, and is of particular utility in machines used in manufacturing 15 boots and shoes to insert short fastenings or slugs in the top lift of the heel of a boot or shoe.

In machines of this class the slugs or other fastenings are made from wire by cutting 20 off pieces of a length required for the fastenings and performing on the pieces so severed such shaping operations as are desired to fit them for insertion in the work. The present invention is particularly concerned 25 with the cutting or shearing mechanism that is employed in these machines to sever the wire for the purpose of forming individual fastenings. Usually it is desirable that such fastenings shall have a smooth flat top 30 surface or head and a point shaped to drive easily into the work. The shearing mechanisms employed are usually arranged to form simultaneously the top of one fastening and the point of the next succeeding fasten- 35 ing, and generally they include a pair of blades or cutters which are relatively movable toward and from each other into and out of engagement with the wire which they are to cut. These cutters generally have 40 sharp cutting edges which become dull very quickly, particularly if considerable care is not exercised in grinding them to avoid drawing their temper; and as soon as they become dull, they fail to make a clean cut. 45 Furthermore, even when they are sharp they do not always make a clean cut for the reason that the wire often breaks before the mechanism can complete the cutting operation. In either case the fastening formed 50 will have a rough top surface, usually with a ridge extending across the surface, or a projection sticking up from it. A fastening of this character is objectionable both because it tends to tear or wear out very

quickly the surface of the abrading tool that 55 is used in buffing the heel bottom or other surface in which the fastening is driven, and also because it presents a rough or ragged appearance in the work. The slugs in the tread face of a well finished heel should 60 present a uniform appearance. This appearance is very readily produced if the slugs are cut off cleanly; but it is obvious that if some of the slugs have a ridged or rough 65 top as just described, a great deal of scouring and buffing will be required to produce this result.

These shearing mechanisms also make a wedge shaped point on the fastenings, which is sometimes objectionable since it causes the 70 fastenings to split certain kinds of stock when driven into it, due to the spreading action of this kind of a point. Moreover, if the shearing members are moved together in the severance of the fastening from the wire 75 so as to form it with a narrow point, the point of the fastening is likely to be upset when it is driven into the work, especially when the fastening is made from zinc wire which is relatively soft and is driven into 80 tough, hard stock. If, on the other hand, the shearing members are not caused to approach each other so as completely to sever the fastening from the wire, the point of the fastening will be blunt and consequent difficulty 85 will be experienced in inserting it into the work. The formation of the fastenings with blunt ends is further objectionable because of the tendency of such fastenings when driven into a top lift, to raise the top lift 90 from the next adjacent lift and produce a crack or check in the lateral surface of the heel.

To devise a cutting or shearing mechanism that will overcome these difficulties, 95 constitutes the general object of the present invention. Stated more specifically, the invention aims to devise a shearing mechanism of the character indicated, which will be more reliable, will require less care and attention, and will be less liable to make imperfect fastenings than those now in use. An important feature of the invention relates to cutters or dies of a novel construction, which materially contribute to the accomplishment of these objects. Preferably, 100 these dies have their active faces formed to make on each fastening a wedge shaped 105

point terminating in a thin flat tip having substantially parallel sides. The thin tip enables the fastening to be readily inserted in the work but extends a short distance only 5 from the thick wedge shaped portion of the point of the fastening so that it will not be turned or upset when the fastening is driven.

In accordance with another feature of the 10 invention, cutters are provided for partially severing a wire the end of which is received in the passage of a throat adjacent to the cutters, and the end of the wire is completely severed from the wire to form a fastening by relative movement of the throat and cutters 15 transversely to the cutting edge of one of the cutters.

Other objects and features of the invention will appear as the description proceeds and will be pointed out in the appended 20 claims.

A convenient embodiment of the invention will now be described in detail as applied to the machine widely known commercially as the Universal slugging machine, and which is shown in the Casgrain Patents No. 786190, granted March 28, 1905, and No. 1017381 granted February 13, 1912. Referring to the accompanying drawings, which show this embodiment of the invention, 30

Figure 1 is an angular view of those parts of a fastening making and inserting mechanism which are necessary to an understanding of the present invention;

35 Figs. 2, 3 and 4 are front elevations, partly in section, of the more important parts of the shearing mechanism, showing successive steps in the shearing operation; and

40 Fig. 5 is an angular view of a fastening formed by this mechanism.

In the drawings, 2 indicates the horn tip, 4 the presser plate, 6 the throat, 8 the driver, and 10 the wire guide, all constructed and 45 arranged substantially as shown in the Casgrain Patent No. 1017381. The part 10 guides the wire W into the passage formed for it in the throat 6, a suitable feeding mechanism (not shown) being provided to 50 feed the wire W into the throat between successive cutting operations, as will be obvious to those skilled in this art. The wire is partly severed by two dies or cutters, 12 and 14 respectively, which are arranged to 55 engage opposite sides of the wire W close to the point where it enters the throat 6. The cutter 12 is adjustably clamped in a stationary holder 16 at one side of the throat 6; while the cutter 14 is secured in 60 a similar clamp on holder 18. This holder is fast on the forward end of a sleeve 20 which is mounted to oscillate about its own axis to move the die or cutter 14 toward and from its companion cutter 12. This 65 movement is produced by means of an arm

22 clamped to the rear end of the sleeve 20 and carrying a roll 24 which runs in a cam path formed in a cam 26 fixed on the main shaft 28 of the machine. A bolt 15 adjustable in the holder 18 backs up the cutter 14 and affords a convenient means for adjusting the cutter. All these parts, with the exception of the cutters, are constructed and operated in the manner shown and described in the Casgrain Patent No. 1017381; and reference should be made to this patent for a detailed description of the general organization of this machine, and the manner in which the parts just described co-operate with the other parts of the machine. 80

The throat 6 is secured fast to the forward end of a rock shaft 30 that extends through the sleeve 20 and carries near its rearward end a small bracket or arm 32, to which is secured a removable block 34 having teeth formed therein that mesh with similar teeth formed in the lower end of a lever arm 36. This arm is pivoted on a stud 38 and carries at its upper end a roll 40 running in a path 42 formed in the end 90 of a cam 44 which is fixed to the shaft 28. It is obvious that as the cam 44 rotates, the connections just described will give to the rock shaft 30, and consequently to the throat 6, a rocking movement about the axis 95 of this shaft. In order to adjust the limits of this movement along the path of movement, the roll 40 is mounted on an eccentric stud 46, which is carried by the upper end of the lever 36. 100

In Figs. 1 and 2 the parts are shown in the wire feeding position; that is, the position in which the feeding mechanism advances into the throat 6 the length of wire required for the next fastening. Fig. 2 105 illustrates the positions that these parts occupy when this feeding operation has just been completed and the cutting operation is about to begin. The cams 26 and 44 are so timed that they move the cutter 14 and 110 throat 6 simultaneously toward the stationary cutter 12. The movement of the cutter 14 forces its edge into one side of the wire W, and this movement together with the movement of the throat, forces the opposite 115 side of the wire against the edge of the stationary cutter 12. The two cutters thus bite into opposite sides of the wire at substantially the same time and notch it to approximately the same depth. When the 120 parts have arrived at substantially the positions in which they are shown in Fig. 3, the movement of the cutter 14 toward its companion cutter 12 is stopped; but the throat 6 continues to move toward the stationary 125 cutter. These two cutters thus grip the wire at the point where they have partially severed it, while the throat 6 shears off the wire against the edge of the cutter 12, and thus completes the severing operation. 130

Since the two cutters engaged the wire at the surface of the throat, a clean cut is produced and a smooth head is formed on the fastening that is cut off at this time.

5 As soon as the severing operation has been completed the fastening F so formed is free to drop through the passage in the throat 6, as shown in Fig. 4. The throat is next moved forward, away from the cutters, 10 to carry the fastening so formed under the driver 8. This movement is effected through a toothed block 50 which is secured to the rearward end of the rock shaft 30, and the teeth of which mesh with similar teeth 15 formed on the lower end of a lever 52, which is fulcrumed at a point above the cam 44 and carries a roll 54 running in the cam path 56 formed in the periphery of the cam 44. As soon as the driver has driven the fastening 20 and moved out of the throat, the throat 6 and the cutter 14 are returned to the positions in which they are shown in Fig. 2, and the cycle of operations just described is then repeated.

25 The arrangement, above described, affords a convenient, compact and efficient shearing mechanism, and constitutes an important feature of this invention. As above indicated, the invention also is directed to a 30 novel cutter construction. As shown in the drawings, the two cutters 12 and 14 instead of having sharp cutting edges, each has a relatively thick substantially plane cutting edge and also has two diverging faces extending backwardly away from said edge. The lower of said faces lies substantially at right angles to the plane of the cutting edge while the upper face is inclined upwardly and backwardly from said edge. These 35 lower faces form a smooth flat head on each fastening and the upper inclined faces form a point that drives easily. While the face or plane of the cutting edge is relatively narrow, still it has sufficient width to render 40 the cutter immune from the objections above described as attending the use of sharp edged cutters. That is, the edge is so thick that it does not become dull quickly, and consequently does not have to be ground 45 frequently, with the resulting danger of drawing the temper at the point where it is most needed. Not only is much of the trouble experienced in using other cutters thus eliminated, but there is substantially 50 less danger of making misshaped fastenings due to the breaking of the wire when notched by the cutters. It has been found in practice that a pair of cutters made as above described often run satisfactorily for 55 months without grinding.

60 It will be evident from an inspection of Fig. 3, that the cutters are so adjusted that their cutting edges, which extend substantially parallel to the length of the wire during the cutting operation, do not quite meet

during the cutting movement, but are stopped when the cutters have partially severed the wire and the throat then continues its movement to complete the severing operation. This method of shearing off the 70 wire, and the peculiar shape of the cutters, produces a fastening having a wedge shaped point that terminates in a thin flat end portion or tip indicated in Fig. 5 at f. It is found in practice that this kind of a point 75 is less liable to split the stock into which it is driven, than is the wedge shaped point more commonly used on fastenings of this character. This apparently is due to the fact that the tip f acts as a broach or punch, 80 and in forcing its way into the stock pushes a certain amount of the stock ahead of it, as does a punch. The wedge shaped portion that follows then crowds aside the stock that remains in the path of the fastening. This 85 feature is of particular value in slugging machines which are used to drive a row of fastenings close together along the margin of the top lift, and in which accordingly, any tendency to split the stock is especially 90 objectionable.

Having thus described my invention, what I claim as new and desire to secure by Letters Patent of the United States is:

1. In a machine for making fastenings 95 from wire, a shearing mechanism constructed to cut the wire to form simultaneously the head of one fastening and the point of the next succeeding fastening, said mechanism including shaping members having 100 their active faces formed to make on each fastening a wedge shaped point terminating in a thin flat tip having substantially parallel sides.

2. In a machine for making fastenings 105 from wire, a shearing mechanism constructed to cut the wire to form a smooth flat head on one fastening and simultaneously therewith to form the point of the next succeeding fastening, said mechanism including dies 110 having their active faces formed to make on each fastening a wedge shaped point terminating in a thin flat tip having substantially parallel sides.

3. In a machine for making fastenings 115 from wire, a shearing mechanism constructed to cut the wire to form simultaneously the head of one fastening and the point of the next succeeding fastening, said mechanism including two cutters mounted for 120 relative movement toward and from each other, operating mechanism for said cutters, said cutters being operated and having their active faces shaped so as partially to sever a wire positioned between them, and form on each fastening a wedge shaped point terminating in a thin flat tip having substantially parallel sides.

4. In a machine for making fastenings 125 from wire, cutters, means for guiding the 130

wire past said cutters to a position such that the free end of the wire extends beyond said cutters to an extent sufficient to form a fastening, each of said cutters having a relatively thick substantially plane cutting edge and two diverging faces extending backwardly away from said edge, one of said diverging faces lying at a substantially right angle to said edge, and said last-mentioned faces being arranged on the sides of the cutters toward the projecting portion of the wire which is to be formed into a fastening.

5. In a machine for making fastenings from wire, the combination with cutters for operating on the wire, a throat into which the end of the wire is fed past said cutters, said cutters having relatively thick substantially plane cutting edges and each having two diverging faces extending backwardly away from said edge, one of said diverging faces lying at a substantially right angle to said edge and said last-mentioned faces being arranged on the sides of the cutters toward said throat.

6. In a machine for making fastenings from wire, the combination with a shearing mechanism for cutting the wire to form simultaneously the head of one fastening and the point of the next succeeding fastening and comprising a pair of cutters, each of said cutters having a relatively thick substantially plane cutting edge and two diverging faces extending backwardly away from said edge, one of said faces lying at substantially right angles to said edge, of mechanism for relatively moving said cutters to cause them to partially sever a wire positioned between them, said mechanism being constructed and arranged to stop said relative movement before said cutting edges meet.

7. In a machine for making fastenings from wire, the combination with a shearing mechanism comprising a pair of cutters, each of said cutters having a relatively thick substantially plane cutting edge and two diverging faces extending backwardly away from said edge, one of said faces lying at substantially right angles to said edge, of mechanism for relatively moving said cutters to cause them to partially sever a wire positioned between them, said mechanism being constructed and arranged to stop said relative movement before said cutting edges meet, a throat in which the end portion of the wire is positioned while said movement of the cutters in a direction transverse to the cutting edge of one of the cutters is being effected, and mechanism for relatively moving said throat and said cutters after the cutters have completed their relative cutting movement and while they grip the wire to complete the severance of the wire.

8. In a machine for making fastenings

from wire, the combination with a throat having a passage to receive the end of a wire, and means for guiding a wire into said passage, of a pair of cutters mounted adjacent to said throat and formed with cutting edges, mechanism for relatively moving said cutters to carry said cutting edges toward each other to partially sever the wire, and means for giving said throat and said cutters a relative movement in a direction to shear off the wire against one of said cutting edges to complete the severance of the wire.

9. In a machine for making fastenings from wire, the combination with a throat having a passage to receive the end of a wire, and means for guiding a wire into said passage, of a pair of cutters mounted adjacent to said throat, one of said cutters being stationary and the other movable, operating mechanisms for simultaneously moving the cutting edge of the movable cutter and said throat toward the cutting edge of the stationary cutter to cause said cutters to notch opposite sides of the wire adjacent to the point where it enters said throat, said throat operating mechanism being operative thereafter to give the throat a further movement serving to shear off the wire against the cutting edge of one of said cutters.

10. In a machine for making fastenings from wire, the combination with a throat having a passage to receive the end of a wire, and means for guiding a wire into said passage, of a pair of cutters mounted adjacent to said throat, mechanism for relatively moving said cutters, means for moving said throat to force the wire against one of said cutters, and means for giving said throat an additional movement away from said cutters at an angle to the first-mentioned movement.

11. In a machine for making fastenings from wire, the combination with a throat having a passage to receive a wire, and means for guiding a wire into said passage, of a stationary cutter mounted adjacent to said throat, a rock shaft supporting said throat, a cam mechanism connected with said rock shaft and operative to swing the throat toward and from said cutter, a sleeve on said rock shaft, a cutter mounted on said sleeve for movement toward and from said stationary cutter, and a cam mechanism for rocking said sleeve independently of said rock shaft.

12. In a machine for making fastenings from wire, the combination with a throat having a passage to receive a wire, and means for guiding the wire into said passage, of a rock shaft supporting said throat, means for rocking said shaft, a stationary cutter against which the wire is forced by the rocking movement of said throat, said

cutter being in a position to engage the wire close to the point at which it enters said throat, another cutter mounted for movement toward and from the first cutter 5 to coöperate therewith in severing the wire, means for operating the latter cutter, and additional means for moving said rock shaft longitudinally of its axis.

13. In a machine for making fastenings 10 from wire, the combination with a shearing mechanism comprising a pair of cutters, each of said cutters having a relatively thick substantially plane cutting edge and two diverging faces extending backward 15 away from said edge, said edge lying substantially parallel to the length of the wire when the cutters are operating on it and

one of said faces lying substantially at right angles to said edge, of means supporting one of said cutters in a stationary position, mechanism for moving the other cutter toward and from the stationary cutter, a throat in which the end portion of the wire is positioned while said cutters operate on it, supporting and operating mechanism 20 for said throat arranged to cause it to force the wire against the stationary cutter at the same time that the movable cutter advances toward the stationary cutter, and means for giving said throat an additional movement away from said cutters. 25

In testimony whereof I have signed my name to this specification.

GEORGE GODDU.

It is hereby certified that in Letters Patent No. 1,348,864, granted August 10, 1920, upon the application of George Goddu, of Winchester, Massachusetts, for an improvement in "Machines for Making Fastenings," an error appears in the printed specification requiring correction as follows: Page 4, lines 58-59, claim 7, strike out the words "in a direction transverse to the cutting edge of one of the cutters," and line 61, after the word "cutters" insert the words *in a direction transverse to the cutting edge of one of the cutters*; and that the said Letters Patent should be read with this correction therein that the same may conform to the record of the case in the Patent Office.

Signed and sealed this 26th day of October, A. D., 1920.

[SEAL.]

L. B. MANN,

Acting Commissioner of Patents

Cl. 10—44.
